DISPENSING APPARATUS

Lue O. Garner and Fred Montesi,
Memphis, Tenn.

Application May 5, 1938, Serial No. 206,133

12 Claims. (Cl. 74—128)

This invention relates to mechanism for dispensing packages or articles such as sandwiches, and to means for heating or retaining the heat in such articles.

6 The invention relates to means by which the sandwiches are stored in the dispensing drum; and to means by which the various movements are accomplished and coordinated to provide a step by step movement for the individual 10 charge of the sandwiches.

The objects of the invention are:

To provide a dispensing apparatus having a carrier in which a large number of articles to be dispensed may be carried, and means for advancing this carrier step by step.

15 To provide means for preventing advancement of the carrier by other than the designated advancing means.

To provide means for limiting the movement 20 of the carrier at any one operation to a single step advancement; and

To provide means for indicating discharge of the last package contained in the apparatus.

25 The means by which the foregoing and other objects are accomplished, and the method of their accomplishment will readily be understood from the accompanying drawings, in which:

Fig. 1 is a sectional elevation of a case having three dispensing carriers therein, a portion of the 30 front of the case being broken away to show one of the carriers and related parts within the case in front elevation, and a second of the carriers in section on the vertical center line through the axis of the carrier.

35 Fig. 2 is a fragmentary section taken as on the line II—II of Figs. 1 and 3.

Fig. 3 is a corresponding fragmentary front elevation of the parts shown in Fig. 2.

40 Fig. 4 is an enlarged fragmentary section showing a switch cooperating with the carrier to indicate that the pocket adjacent the delivery chute is empty.

Fig. 5 is a sectional plan of the device, a portion 45 of the top being broken away to show the carriers in plan.

Fig. 6 is a sectional elevation taken on the line VI—VI of Fig. 4.

Fig. 7 is a fragmentary sectional elevation on an enlarged scale showing the carrier advancing 50 mechanism; and

Fig. 8 a fragmentary plan of the same parts.

Fig. 9 is a fragmentary section taken on the line IX—IX of Fig. 7.

55 Referring now to the drawings in which the various parts are indicated by numerals:

10 is a casing having insulated side, bottom and top walls, the front half of the top wall being divided into doors or sections 11, 12 and 13. The doors 11, 12 and 13 are hinged at their rear ends as by hinges 14 and are each provided at their forward ends with a hasp and staple 15, with which a suitable lock (not here shown) may be used, the doors thus formed being openable to replenish the stock of sandwiches in the carriers, or for other access to the interior of the casing. 10

Disposed within the casing are three frames 20, built preferably of angle-iron, there being one frame for each carrier. These frames have each a pair of angle-iron members 21, which members support bearings 22. Each carrier is provided with a shaft 23, journalled in a pair of these bearings. Secured to the shaft 23, as by a pin 24, is a hub 25. 26 is a disc concentric with the shaft 23 and secured to the hub 25 as by rivets 27. The periphery of the disc 26 is partially cut away 20 to leave protruding equally spaced lugs 28, there being one lug for each of the article holding pockets. 29 is a cylindrical shell concentric with shaft 23 and having flanged portions 30 which are secured to the disc 26 as by rivets 31. 25

At its opposite end the shell 29 is provided with flange portions 32 which are secured as by rivets to an annular disc 33. 34 are a plurality of radially disposed partitions which extend from the shell 29 outward between the discs 26 and 33, 30 being secured to these discs as by welding. The spaces between the partitions, form pockets 35, in which pockets the individual packages are disposed.

The carriers thus constructed are given a step 35 by step movement by plungers 40, there being an individual plunger for each carrier, these plungers are coupled to, and their movement controlled, by coin control mechanisms 41, one for each plunger, these mechanisms being purchasable in 40 the open market and described in detail in patents such as #2,025,921, January 7, 1936. For each plunger there is a plunger arm 42 which is hingedly connected as by a pin 43 to a plunger link 44. The plunger link 44 has a fork 45 which 45 rides on the peripheral edge of the disc 26, the end 46 of the link engaging the lugs 28 of the disc successively and shifting the disc one lug space, that is, pocket space, for each inward thrust of the plunger. It will be noted that the 50 link has a limited movement along the periphery of the disc 26 before engagement of the end 46 of the link with the lug 28 takes place.

Disposed above the link 44 is a latch arm 50 hingedly connected as by a pin 51 to a portion 52. 55

of the carrier supporting frame 20. The latch arm 50 is downwardly bent at its outer end to form a lug engaging latch 53, the lower end of this latch being provided with a slot 54 which 5 is adapted to receive the edge of the disc 26 and prevent lateral displacement of the latch, the depth of the slot being somewhat greater than the depth of the lugs 28, in order that the latch may be raised to free the lugs and yet not be 10 displaceable sidewise from the disc. 55 is a leaf spring secured as by screws 56 to the frame member 52, which spring urges the latch 53 into lug engagement. 57 is a rocker latch bar hingedly mounted as on a pin 58 and having one end re- 15 silently urged into engagement with the latch arm 50 by a spring 59. At its opposite end the rocker bar carries a downwardly turned latch portion 60, substantially identical in construction with the latch 53. Secured to the under side of 20 the latch arm 50 is a cam member 61 which is adapted to be engaged and raised by a cam 62. Cam 62 is pivotally mounted on the link 44 by a pivot pin 63. 64 is a stop, and 65 a spring urging the cam 62 against the stop.

25 70 are discharge chutes, there being one for each of the carriers. These discharge chutes extend from the exterior of the casing 10 through suitable openings therein into proximity to the periphery of the carrier.

30 71 are arcuate bands one for each carrier. Each band is concentric with, and lies adjacent the periphery of its carrier, though not necessarily in intimate proximity thereto. The band is supported at one end by a frame member 35 12, about level with the center of the carrier, and at its opposite end as by a bar 73, also forming a part of the frame.

From the bar end of each frame, a continuing arcuate extension band 74 extends above 40 the carrier center and has side walls 75 extending into supporting engagement with the frame 20. Each band is interrupted or otherwise provided with an opening 76 which is aligned with the chute 70 so that when any pocket of 45 the carrier reaches the pocket position 35-A, Fig. 6, it comes into alignment with the opening 76 and the chute 70, and the content of the pocket is free to slide outward and discharge through the opening and into the chute. 77

50 78 is an arcuate shutter exterior to the band 74, this shutter having an opening 79, shown in register with the opening 76, and being slidably mounted so that it may be shifted with respect to the band to close the opening. 79

55 80 are guides holding the shutter 77 in such slide- able engagement. At its upper end the shutter 77 is provided with an outwardly turned flange or lug 80. 81 is a chain secured at one end to the lug and at the opposite end supported 60 as by a pin 82 extending from the carrier frame. The shutter 77 is shiftable when its corresponding door (11, 12 or 13) is open, by pulling upward on the chain 81 to shift the shutter opening 78 relative to the opening 76, and effect 65 closing of the latter opening during filling of the pockets.

85 86 is a dog pivotally secured as through a pin, and bracket 86, to a frame member 87, this dog being resiliently urged by a spring 88 70 into engagement with the lugs 28 in succession to prevent retrogressive movement of the carrier.

89 is an electrical heating pad substantially concentric with and lying adjacent to the cylindrical portion 29 of the carrier. This pad is 75 supported by frame members 90. 91 is a cable

carrying circuit wires 92 leading to this heating pad, the cable 91 having a continuation 93 extending beyond the casing and leading from a suitable source of current.

95 is a bracket secured to the bar 73. 96 is 5 a block of insulating material fixedly carried by the bracket 95; 97 a contact point carried by the block, and 98 a circuit lead. 99 is a second block of insulation carrying a complementary contact point 100. The block 99 is 10 pivotably carried by the bracket 95 and has an arm 101 which extends through a slot 102 in the slide 71, and through an opening 103 in the band extension 74 and has an extension 104 15 adapted to be held against the inner surface of the band 74 by an article, such as a sandwich, 105, within the pocket in the position 35-B adjacent the openings 76 and 78. 106 is a spring 20 acting on the arm 101, which spring when the pocket in the position 35-A is empty, brings the points 97 and 100 into contact, and completes the circuit to a signal light 107 on the front of the casing, indicating that the pocket is empty.

25 In the use of the device, one of the doors (11, 12 or 13) covering a carrier therebelow is opened and the sandwiches or other articles to be dispensed are dropped into the pockets 35, the latch arm 50 being raised from engagement with the lugs 28 and the carrier being advanced 30 step by step as filling is carried on. As filling progresses the filled pockets move toward alignment with the openings 76 and 78, through which discharge is effected into the chute 70. At some 35 time before this point is reached the chain 84 is grasped and the shutter 77 raised to close the opening 76 and permit complete filling of all the pockets. After filling has been accomplished the chain 84 is released and the shutter 77 allowed to drop to place, reestablishing alignment of the openings 76 and 78 and allowing immediate discharge of the article from the pocket which is in the position 35-A. The door above the carrier is then closed and locked, the operation being repeated for each of the 45 three carriers shown, or for as many carriers as there may be, should the casings accommodate a different number than are shown.

With the carriers filled, the customer drops a coin of the proper denomination in the coin 50 slot of the coin control apparatus 41 and pushes in the plunger 40 related thereto. This inward movement slides the fork 45 along the rim of the disc 26 and brings the cam 62 into engagement with the cam member 61, and, the movement of the plunger continuing, raises the latch arm 50. This movement disengages the latch 53 from lug engagement at about the same time that the end 46 of the plunger engages a lug in the position 28-A. Raising movement of 60 the latch 53 to accomplish this disengagement tilts the arm 57 upward, where it rests on top of the latch arm 50, and moves the latch 60 downward into the path of a lug in the position 28-B. Continued movement of the plunger 42 65 shifts the disc 26 a full pocket space. In accomplishing this shift the cam 62 slides under the cam member 61 during the time that it is necessary for the latch 53 to be raised to permit the passage therebeneath of a lug moving from 70 the position 28-C, and after such lug movement has been accomplished the cam clears the cam member 61, allowing the latch arm 50 to drop and the latch 53 to resume lug engaging position. This movement also permits the cam 57 75

and its latch 60 to return to disengaged position. The advance of the disc thus accomplished is retained by the dog 85 and the cycle is completed by retraction of the plunger 42, the cam 62 in such movement tripping about the pin 63 and against the resistance of the spring 65 to permit such movement without raise of the cam arm 50.

As the inward movement of the plunger 42 is completed another of the pockets in the carrier moves to the position 35—A with the division wall 34, which forms the bottom of the pocket, so lined up with the openings 76 and 78, that the discharge of the article, through the pocket and through the discharge chute 79, may be accomplished by gravity. During their stay in the carrier the sandwiches may be heated by turning on current through the heater 90.

It will be noted that should someone try to advance the carrier in unauthorized manner, as by inserting their hand through the openings 76 and 78, the latching mechanism, above described, would effectually prevent such action.

It will be understood that while the primary purpose for which this device has been built is the dispensing of sandwiches, that its use for other purposes and for the dispensing of other articles is also contemplated and that the use of the word "sandwich" therefore in the specification is not intended to so limit the use of the device.

It will also be understood that the shape of the pockets may be such as is necessary or desirable to conform them to the shape of other articles, such for example as cylindrical cans.

We claim:

1. Operating mechanism for a vending machine having a casing enclosed, rotary dispensing drum with projecting, equally spaced lugs and coordinated dispensing pockets, said mechanism including a plunger slidably mounted through a wall of said casing and manually reciprocable, the longitudinal axis of said plunger lying substantially tangent to said drum, said plunger having an end portion resting on, and adapted to slide along the circumference of said drum into actuating engagement with each of said lugs in succession and on continuing movement to shift said drum, an arm hingedly secured to said casing, said arm having at its free end a downwardly turned stop adapted to ride on the circumference of said drum and engage said lugs in succession to limit their movement, means urging said stop into lug engagement, means carried by said plunger, and cooperative means carried by said arm, adapted on inward movement of said plunger, to engage and raise said stop out of the path of said lugs as the end of said plunger approaches engagement with a lug, said cooperative means being coordinated to pass as plunger movement continues and permit said stop to reseat on said drum and engage and stop the movement of the next following lug and thereby limit turning movement of said drum; means carried by said casing and engaging said drum to prevent retroactive movement thereof; a rocker arm pivoted adjacent its mid point to said casing, means urging one end of said rocker arm against the top of the free end of said first arm, said second arm having at its opposite end a stop portion normally held by said spring action clear of the path of said lugs, and adjacent but rearwardly as regards directional movement to a said lug, said second arm being tilted by raising of said

first arm to bring its said stop into the path of the next succeeding lug.

2. Operating mechanism for a vending machine having a casing-enclosed, rotary dispensing drum with projecting, equally spaced lugs and coordinated dispensing pockets; said mechanism including a plunger slidably mounted through a wall of said casing and manually reciprocable, the longitudinal axis of said plunger lying substantially tangent to said drum, said plunger having an end portion resting on, and adapted to slide along the circumference of said drum into actuating engagement with each of said lugs in succession and on continuing movement to shift said drum; an arm hingedly secured to said casing, said arm having at its free end a downwardly turned stop adapted to ride on the circumference of said drum and engage said lugs in succession to limit their movement, said stop being slotted to prevent lateral movement, resilient means urging said stop into lug engagement, means carried by said plunger, and cooperative means carried by said arm, adapted on inward movement of said plunger, to engage and raise said stop out of the path of said lugs as the end of said plunger approaches engagement with a lug, said cooperative means being coordinated to pass as plunger movement continues and permit said stop to reseat on said drum and stop the movement of the next following lug, thereby limiting turning movement of said drum, ratchet means carried by said casing and engaging said drum to prevent retroactive movement thereof, a rocker arm pivoted adjacent its mid point to said casing, a spring urging one end of said rocker arm against the top of the free end of said first arm, said second arm having at its opposite end a stop portion normally held by said spring action clear of the path of said lugs, and adjacent but rearwardly, as regards directional movement, to a said lug, said stop portion being slotted to prevent lateral movement, said second arm being tilted by raising of said first arm to bring its said stop into the path of the next succeeding lug.

3. Operating mechanism for a vending machine having a casing-enclosed, rotary dispensing pockets; said mechanism including a plunger having its longitudinal axis in the plane of said lugs and slidably mounted through a wall of said casing and manually reciprocable, said plunger having an end portion resting on the circumference of said drum and being adapted to slide therealong into actuating engagement with a said lug, and on progressive movement to shift said drum; an arm hingedly secured to said casing, said arm having at its free end a downwardly turned stop adapted to ride on the circumference of said drum and engage said lugs in succession to limit their movement, resilient means urging said stop into lug engagement, a cam pivotally connected to said plunger, a stop on said plunger limiting retrogressive movement of said cam at an operative position of said cam, a spring urging said cam against said stop, a cam member on said arm in the path of movement of said cam, said cam and cam member having cooperating surfaces adapted, on inward movement of said plunger, to raise said stop out of the path of said lugs as the end of said plunger engages a said lug, the thickness of said cam and cam member being such as to permit said cam to pass said cam member, shortly after the passage of a lug beyond said stop, permitting said stop to reseat on said drum edge and engage and stop the movement of the next following lug; and means

carried by said casing and engaging said drum to prevent retroactive movement thereof.

4. Operating mechanism for a vending machine having a casing-enclosed, rotary dispensing drum with projecting, equally spaced lugs and coordinated dispensing pockets; said mechanism including a plunger slidably mounted through a wall of said casing and manually reciprocable, the longitudinal axis of said plunger lying substantially tangent to said drum, said plunger having an end portion resting on, and adapted to slide along the circumference of said drum into actuating engagement with each of said lugs in succession and on continuing movement to shift said drum, an arm hingedly secured to said casing, said arm having at its free end a downwardly turned stop adapted to ride on the circumference of said drum and engage said lugs in succession to limit their movement, means urging said stop into lug engagement, means carried by said plunger and cooperative means carried by said arm, adapted, on inward movement of said plunger, to engage and raise said stop out of the path of said lugs as the end of said plunger approaches engagement with a lug, said cooperative means being coordinated to pass as plunger movement continues and permit said stop to reseat on said drum and engage and stop the movement of the next following lug and thereby limit turning movement of said drum; and means carried by said casing and engaging said drum to prevent retroactive movement thereof.

5. Operating mechanism for a vending machine having a casing-enclosed, rotary dispensing drum with projecting, equally spaced lugs and coordinated dispensing pockets; said mechanism including a plunger slidably mounted through a wall of said casing and manually reciprocable, the longitudinal axis of said plunger lying substantially tangent to said drum, said plunger having an end portion resting on, and adapted to slide along the circumference of said drum into actuating engagement with each of said disc lugs in succession and on continuing movement to shift said drum, an arm hingedly secured to said casing, said arm having at its free end a downwardly turned stop adapted to ride on the circumference of said drum and engage said lugs in succession to limit their movement, said stop being slotted to prevent lateral movement, resilient means urging said stop into lug engagement with said drum, means carried by said plunger, and cooperative means carried by said arm, adapted, on inward movement of said plunger, to engage and raise said stop out of the path of said lugs as the end of said plunger approaches engagement with a lug, said cooperative means being coordinated to pass as plunger movement continues and permit said stop to reseat on said drum and stop the movement of the next following lug, thereby limiting turning movement of said drum, and ratchet means carried by said casing and engaging said drum to prevent retroactive movement thereof.

6. Operating mechanism for a vending machine having a casing-enclosed, rotary dispensing drum with projecting, equally spaced lugs and coordinated dispensing pockets; said mechanism including a member having a portion exterior to said casing, said member extending through a wall of said casing and being slidably shiftable into operative engagement with each of said lugs successively, a first means disposed in the path of said lugs adjacent and forward of a said lug, a second means disposed out of the path of said lugs and adjacent but rearward of a said lug,

means carried by said first means engageable by said member to displace said first means from said lug path during passage of said adjacent lug, means carried by said second means engageable by said first means to concurrently dispose said second means in the path of said lugs, and means for restoring said first and second means respectively to their initial positions, after lug movement past said first means.

7. Operating mechanism for a vending machine having a casing-enclosed, rotary dispensing drum with projecting, equally spaced lugs and coordinated dispensing pockets; said mechanism including a member having a portion exterior to said casing, said member extending through a wall of said casing and being slidably shiftable into operative engagement with each of said lugs successively, a first means disposed in the path of said lugs adjacent and forward of a said lug, a second means disposed out of the path of said lugs and adjacent but rearward of a said lug, means carried by said first means engageable by said member to displace said first means from said lug path during passage of said adjacent lug; means carried by said second means engageable by said first means to concurrently dispose said second means in the path of said lugs, means for restoring said first and second means respectively to their initial positions, after lug movement past said first means, and ratchet means engaging said lugs successively to prevent retrogressive movement of said drum.

8. Operating mechanism for a vending machine having a casing-enclosed, rotary dispensing drum with projecting, equally spaced lugs and coordinated pockets; said mechanism including a reciprocable plunger slidably mounted through a wall of said casing, said plunger having an end portion adapted to operatively engage each of said lugs in succession and on continuing movement, to shift said drum; a first arm hingedly secured to said casing, said arm having at its free end a downwardly turned stop, adapted to engage said lugs in succession to limit their movement, means urging said stop into lug-engagement, means carried by said plunger and cooperative means carried by said arm, adapted, on inward movement of said plunger, to raise said stop out of lug-engagement as the end of said plunger approaches engagement with a lug, said cooperative means being coordinated to pass, as plunger movement continues, and permit said stop to engage and stop the movement of the next following lug and thereby limit turning movement of said drum; means carried by said casing and engaging said drum to prevent retroactive movement thereof; a rocker arm pivoted adjacent its mid point to said casing, means urging one end of said rocker arm against the top of the free end of said first arm, said rocker arm having at its opposite end a stop portion normally held by said urging means clear of lug engagement, and adjacent but rearwardly, as regards directional movement, to a said lug, said rocker arm being tilted by raising of said first arm to bring its said stop into the path of the next succeeding lug.

9. Operating mechanism for a vending machine having a casing-enclosed, rotary dispensing drum with projecting, equally spaced lugs and coordinated dispensing pockets; said mechanism including a reciprocable plunger slidably mounted through a wall of said casing, said plunger having an end portion adapted to operatively engage each of said lugs in succession and on continuing

- movement to shift said drum, an arm secured to said casing, said arm having a movable end, said end having a downwardly turned stop adapted to engage said lugs in succession to limit their movement, said stop being slotted to prevent lateral movement, resilient means urging said stop into lug engagement, means carried by said plunger and cooperative means carried by said arm, adapted on inward movement of said plunger, to raise said stop out of lug-engagement as the end of said plunger approaches engagement with a lug, said plunger means and said cooperative means being coordinated to pass, as plunger movement continues, and permit said stop to check the movement of the next following lug, thereby limiting turning movement of said drum; ratchet means carried by said casing and engaging said drum to prevent retroactive movement thereof; a rocker arm pivoted adjacent its mid point to said casing, a spring urging one end of said rocker arm against the top of the free end of said first arm, said rocker arm having at its opposite end a stop portion normally held by said spring action clear of lug engagement, said stop portion being positioned adjacent but rearwardly as regards directional movement to a said lug, said second arm being tilted, by raising of said first arm, to bring its said stop portion into engagement with the next succeeding lug.
10. Operating mechanism for a vending machine having a casing-enclosed, rotary dispensing drum with projecting, equally spaced lugs and coordinated dispensing pockets; said mechanism including a reciprocable plunger, slidably mounted through a wall of said casing, said plunger having an end portion adapted to operatively and successively engage said lugs, and on progressive movement to shift said drum; an arm hingedly secured to said casing, said arm having at its free end a downwardly turned stop adapted to engage said lugs to limit their movement, means urging said stop into lug engagement, a cam pivotally connected to said plunger, a stop on said plunger limiting retrogressive movement of said cam at an operative position of said cam, a spring urging said cam against said stop, a cam member on said arm in the path of movement of said cam, said cam and cam member having cooperative surfaces adapted, on inward movement of said plunger, to raise said stop out of lug-engagement as the end of said plunger engages a said lug, the thickness of said cam and cam member being such as to permit said cam to pass said cam member, shortly after the passage of a lug beyond said stop, permitting said stop to engage and stop the movement of the next following lug;
11. Operating mechanism for a vending machine having a casing-enclosed, rotary dispensing drum with projecting, equally spaced lugs and coordinated dispensing pockets; said mechanism including a reciprocable plunger mounted through a wall of said casing, said plunger being adapted to successively engage each of said lugs and on continuing movement to shift said drum, an arm secured to said casing and having a downwardly turned end portion, said end portion being adapted to engage said lugs to limit their movement, means urging said end portion into lug engagement, means carried by said plunger and cooperative means carried by said arm, adapted, on inward movement of said plunger, to raise said end portion out of lug-engagement, said cooperative means being coordinated to pass said plunger-means as plunger movement continues and permit said end portion to be reestablished in the path of movement of the next following lug, and thereby limit turning movement of said drum; and means carried by said casing adapted to prevent retroactive movement of the said drum.
12. Operating mechanism for a vending machine having a casing-enclosed, rotary dispensing drum with projecting, equally spaced lugs and coordinated dispensing pockets; said mechanism including a reciprocable plunger slidably mounted through a wall of said casing, said plunger being adapted to operatively engage each of said lugs in succession and on continuing movement to shift said drum, an arm hingedly secured to said casing, said arm having at its free end a downwardly turned stop portion adapted to engage said lugs in succession to limit their movement, said stop being slotted to prevent lateral movement, means urging said stop into lug-engagement, means carried by said plunger and cooperative means carried by said arm adapted, on inward movement of said plunger, to engage and raise said stop out of lug engagement as the end of said plunger approaches engagement with a lug, said cooperative means being coordinated to pass as plunger movement continues and permit said stop to check the movement of the next following lug, thereby limiting turning movement of said drum; and ratchet means carried by said casing adapted to prevent retroactive movement of the said drum.

LUE O. GARNER.
